GASIFYING OIL BURNER FOR HEATING PURPOSES

George M. Burgess, La Fayette, Ind.

Application April 30, 1947, Serial No. 744,972

10 Claims. (Cl. 158—53)

1

This invention relates to an oil burner of general use for heating purposes and especially adapted for use in heating furnaces, and to automatic control thereof.

It is the object of my invention to provide an oil burning device for heating purposes, which will be reliable, safe, and efficient; which will be adaptable to use in various installations, and is especially suitable for use in domestic furnaces; and which will provide desirable and adequate automatic controls to regulate the operation of the device under the various conditions of operation. It is a special object of my invention to provide a simple and practical device which will effect thorough gasification of fuel oil prior to its admixture with air for combustion, will then combine the gasified fuel oil with air in an efficient combustible mixture, in a system that lends itself to automatic control and to automatic ignition; to provide a reliable and rapid starting operation in such a device; to provide simple and reliable controls in combination with such system; to provide in the starting and controls a progressive operation, such for example that interruption of the starting cycle at any point will automatically prevent initiation of subsequent operations in such cycle; and to combine the accomplishment of such several objects in a combination installation unit, which unit will have a minimum of operating parts and no mechanically operating parts subjected to high temperature, which will be convenient, practical, and inexpensive to manufacture, which will readily lend itself to application in a wide variety of installations, will require a minimum of servicing in such installations and will be convenient for any such servicing that may be required.

In accordance with my invention, combustion is caused to take place in part of a firing chamber which is conveniently tubular in form and which I may call a "firing tube." The incoming fuel oil is fed under low pressure to gasifying chamber positioned to receive heat for effective and self-sustaining oil gasification from combustion in the firing chamber, desirably through a wall thereof. The gasified oil is discharged into the tube, through ports which impose little or no back pressure and open from the periphery of the tube, and the gasified oil is mixed with air fed axially through the tube, into an efficient combustible mixture. An independent source of initial gasifying heat to the gasifying chamber is provided for starting.

Desirably, the gasifying chamber is maintained empty or substantially empty under stand-by

2

operation, oil supplied thereto for heating operation is admitted under low pressure at a controlled rate, and the gasifying chamber presents a surface at a temperature to gasify the oil initially admitted thereto at the controlled rate. This provides an immediate initial supply of gasified oil to start combustion, which progressively provides additional heat to progressively gasify the progressively incoming supply of oil, and the progressive action quickly establishes self-supporting gasification and combustion at a continuous-operation rate.

In the self-sustained full operation which ensues, the firing tube wall of the gasifying chamber is maintained at a high temperature, for example at red heat, to effectively gasify the oil for highly efficient combustion.

Heating means for the initial gasifying surface, and primary ignition means, may be of any of several types, electric, gas, or oil operated. I prefer to employ a continuously operating heating means, with either gas or oil as its fuel, and to use a pilot flame from the same source for ignition in the starting-cycle.

Change from full operation to stand-by operation and vice versa may be effected by a simple shut-off valve in the incoming oil line, and any desired change in air supply between stand-by and full operation is preferably under a control responsive to a condition of established combustion, for example the temperature thereof.

Desirably, the gasifying chamber has its oil inlet at or near its bottom and its gas outlet at or near the top, and the oil supply is controlled at a constant level between such inlet and outlet.

In a preferred form of my invention, the oil flow, under constant level control and low head, leads through the shut-off valve and a metering valve to a gasifying chamber inlet positioned adjacent the flame-discharge end of the firing tube and a short distance below the oil level of constant control. The gasifying chamber is annular, surrounding the firing tube, and has a gas outlet at the top, above the constant oil level, to a manifold which also receives heat from the firing tube and which distributes the hot gasified oil to fuel ports in the wall of the firing tube. During stand-by operation, independent heating means maintains a lower part of the gasifying chamber at initial gasifying temperature, as by a continuously burning gas or oil flame, and such heating means may also provide a pilot flame. Preferably, the independent heater is positioned outside the combustion tube and heats a portion of the outer wall of the gasifying cham-

ber, so that its operation is substantially independent of conditions within the firing tube, and where it may be independently housed for controlled reliable operation.

The oil control valve is desirably one whose normal position is closed, and which during demand for heat of full operation is opened and held open by electrical means. Air for stand-by operation and for initial combustion in the starting cycle is desirably supplied by natural draft. When initial combustion is established, an additional supply of air is provided by a blower, controlled in response to the temperature in the firing tube, and desirably operated from the same electrical source as the oil control valve.

My oil burner is of relatively simple construction, and its controls and many of its parts may be of standard form and operation. Preferably, its firing tube assembly is of cylindrical tubular stock, but it may be of other form and material. The firing tube assembly may be, and desirably is, a self contained unit which may be made in various sizes and forms for selective combination with an operating unit to meet the requirements of a particular installation. It may be mounted in any desired position, to discharge horizontally, vertically, or at some intermediate angle.

My burner is readily adaptable to the usual thermostatic control, for its whole operation may be, and normally is, controlled by the single shut-off valve in the oil supply line, which may be made responsive to the usual room thermostat, or to the combined control of a room thermostat and a limit control, or to other desired or usual control devices.

The accompanying drawings illustrate my invention. In such drawings, Fig. 1 is a plan of an oil burner unit embodying my invention; Fig. 2 is a side elevation of the unit shown in Fig. 1, with the firing tube assembly shown in section; Fig. 3 is an elevation, taken from the opposite side of Fig. 1, and showing details of the blower inlet; Fig. 4 is a vertical section taken at the flame-discharge end of the firing tube, on the line 4—4 of Fig. 2; Fig. 5 is a fragmental horizontal section on the line 5—5 of Fig. 4, showing details of the gas burner used in this modification as the independent source of heat for the gasifying chamber; Fig. 6 is a vertical longitudinal section of a modified form of firing tube assembly interchangeable with that shown in Figs. 1 to 4, and in which the firing tube discharges vertically against a baffle; Fig. 7 is a vertical longitudinal section of another modification of a firing tube assembly, also interchangeable with that of Figs. 1 to 4; and Fig. 8 is a horizontal section taken on the line 8—8 of Fig. 7.

The oil burner shown in Figs. 1 to 5 comprises a firing tube assembly A, shown in section in Fig. 2, and an operating assembly, embodying fuel and air supply and control devices mounted on a common base B, and providing an upright wall by which the firing tube assembly is detachably secured to the operating assembly.

The firing tube assembly, shown projecting through a wall 11 of a furnace into the combustion chamber thereof, comprises a firing tube 10 of heat resistant sheet metal (e. g. of 3 inch inside diameter), fully open at its flame discharge end, shown to the left in Fig. 2. Its opposite end is open to the discharge of a blower 12 driven by a motor 13 (e. g. of $\frac{1}{20}$ horsepower) and having an intake 14 controlled by adjustable vanes 15. Desirably, such inlet is below the out-

let into the firing tube 10, to promote natural draft therethrough for the starting cycle.

The firing tube 10 is surrounded by a tube 20, spaced from the firing tube 10. The space between the two tubes 10 and 20 is sealed at the front and rear ends of the tube 20, as by rings 22 and 24 welded to the two tubes. The two tubes 10 and 20 are also joined over most of their circumference by a dividing part-ring 25 welded to the tube 10 before assembly and welded to the outer tube 20 through a slot which overlies the part-ring 25. The part-ring 25 divides the space between the two tubes 10 and 20 into a gasifying chamber 21 and a manifold 27, and leaves a gas outlet 26 at the top of the gasifying chamber 21 leading to the manifold 27. Such manifold 27 communicates with the interior of the tube 10 through a circumferentially spaced series of fuel ports 30 in the firing tube wall. An oil supply pipe 31 extends forwardly beneath the gasifying chamber 21 at its bottom, and desirably at a point near the front of the firing tube 10.

For starting, the gasifying chamber 21 is supplied with a source of heat independent of combustion in the firing tube 10. Such independent source of heat may be an oil burning device, or may take various other forms, as indicated above. As shown, the independent source of heat is a gas burner 40 positioned beneath the gasifying chamber 21, and provided with a series of burner ports beneath a bottom portion of the outer wall 20 of the gasifying chamber 21. In addition, the gas line extends forward to the end of the firing tube 10, and is there provided with a burner port 41 to provide a flame for ignition. During stand-by operation, this gas burner 40 heats the bottom portion of the gasifying chamber to initial gasifying temperature and the gas burner 41 provides a pilot flame, to maintain the installation ready to meet any demand for heat. Gas is supplied to the burners 40 and 41 through a supply pipe 43, which may be connected to a source of supply through a pressure regulator 42.

The wall of the firing tube 10 extends rearwardly to a mounting plate 46 and is welded thereto. The wall 20 of the gasifying chamber 21 is desirably terminated immediately behind the manifold 27, and at this point there is a dividing wall 47 through which the firing tube passes. The walls 46 and 47 extend downward below the firing tube, where they are interconnected by a tube through which the gas burner 40 extends and which is sufficiently larger than such gas burner 40 to provide a passage for secondary air to that burner. The oil supply pipe 31 also passes through the two walls 46 and 47 and is desirably tack welded thereto.

An outer cover wall 48 for the firing tube assembly extends from the rear mounting wall 46 forward to the end of the outer wall 20 of the gasifying chamber, and is supported thereby and by the walls 46 and 47. The space between the walls 46 and 47 and enclosed by the casing wall 48 is desirably packed with insulating material.

The casing wall 48 forms an enclosure for the firing tube assembly and the gas burner and oil oil pipe which are located below it, to facilitate control of the gas burner and retain its heat. The forward end of the assembly is desirably closed by a cap 49 which may have an in-turned flange aligned with the firing tube wall 10, in which case such flange is suitably cut away at the bottom to pass the pilot flame from the burner 41 and to provide an outlet from within

the casing 48. The rear ends of the burner 40 and of the oil supply pipe 31 are joined to their supply lines by releasable unions, and the whole firing tube assembly is mounted on the upright wall of the base B by cap screws, so that the whole firing tube assembly may readily be separated from the base B and from the operating assembly which it supports.

Oil is supplied to the burner unit from any desired source through a filter 32, and passes therefrom through a connecting pipe 33 to a constant level device 34 adapted to maintain oil at the level indicated by the oil level marks 35. From the constant level device 34 the line of oil flow is through a shut-off valve 36, which is solenoid operated to open position, and through a metering device 37, which may be either adjustable or of the fixed orifice type, and thence by a pipe line 38 which includes a separable union, to the pipe 31 to the gasifying chamber 21.

The blower 12 is controlled to come into operation upon the establishment of combustion in the firing tube. Desirably, such control is by a thermostatic device 50 within the firing tube 10. As shown, such device 50 embodies a thermocouple sealed within a heat resistant capsule positioned on the axis of the firing tube 10 and ahead of the ports 30, and is connected to a blower control relay 51.

Electric current for operating the blower motor 13 and the shut-off valve 36 may be supplied through a cable 60 to a junction box 61. The motor 13 is connected to such source of current through a cable 62, under the control of the relay 51 connected to the junction box 61 by cable 63. The room thermostat (not shown) and any limit control which may be used are connected through the junction box 61, as by cables 64 and 65. Such controls are connected in the usual way, and operate the shut-off valve 36 of the oil supply line, which is connected into the junction box by the cable 66.

During stand-by operation of the device shown in Figs. 1 to 5, the gas burner 40-41 will continuously supply heat to a bottom portion of the gasifying chamber 21 and will maintain a continuous pilot flame. The gasifying chamber 21, when the oil control valve 36 is in off position, will normally be empty, so that the continuously heated portion of the gasifying chamber will receive no oil and will produce no gas. When the thermostatic controls connected by the cables 64 and 65 call for heat, the control valve 36 will be opened, and oil will flow under a low head from the constant level control device 34 through the metering valve 37 and pipes 38 and 31 to the gasifying chamber 21. The rate of such flow will be limited by the metering valve 37 and oil will enter the gasifying chamber slowly. For example, a common rate of oil consumption during full operation of an oil burner in a domestic installation is about 1 gallon of oil per hour. The metering valve 37 will be set to provide an orifice to pass oil at the desired rate for such full operation, and will limit the oil supply at that rate during the starting cycle.

As oil thus slowly enters the gasifying chamber 21 it will come into contact with the heated bottom surface of the gasifying chamber wall and initial gasification will occur. The initial supply of gas so produced will pass from the gasifying chamber through the outlet 26 into the manifold 27, and will be discharged into the firing tube 10 through the ports 30. The blower

will be inoperative, but will pass sufficient air to mix with the initial gasified fuel to form a combustible mixture which will be ignited at the end of the tube 10 by the pilot flame emerging from the burner 41. For the initial gasification, there will be a considerable supply of heat stored in the walls of the gasifying chamber from the continuous operation of the stand-by burner 40, and often also from a preceding cycle of full operation.

Because the initial gasification is in the nature of a flash-vaporization, by the use of this stored heat, the stand-by burner 40 need have but a small flame and hence may be operated at minimum expense. Moreover, initial gasification is produced immediately, and the starting cycle need not wait for any body of oil or for any oil container to be heated to gasifying temperature. Further, the immediate supply of flash-gasified fuel is adequate to support combustion in the firing tube, which makes for safety.

This initial combustion will in turn progressively heat the gasifying chamber 21 through the wall 10 of the firing tube, and progressively create a greater discharge of gasified fuel through the ports 30. The quantity and temperature of combustion will progressively and rapidly increase in this starting cycle, and the temperature in the firing tube 10 will rapidly rise to a point to cause the thermostat device 50 to operate the relay 51 and start the blower 12. By this time, combustion will be well established, so that there will be no chance that the increased supply of air will extinguish the flame. On the contrary, combustion at full operating rate will promptly occur, usually within about a minute after initial opening of the shut-off valve 36, and from then on the whole gasifying and firing operation will be self-sustaining as long as the oil shut-off valve 36 remains open.

Under sustained or full operation, a considerable portion of the base of the flame will be surrounded by that portion of the firing tube which carries the gasifying chamber, and the firing tube wall of the gasifying chamber, and indeed much of the rest of the gasifying chamber, will be maintained at a high temperature, for example at red heat. The oil supplied to the gasifying chamber at the rate determined by the metering valve 37 will be promptly and thoroughly gasified in the gasifying chamber. The resulting gas will be highly heated as it flows about the firing tube wall to the outlet 26 and through the manifold 27. The highly heated gas will be distributed in the manifold 27 to the several ports 30 and will pass through them into the firing tube. As the gasified oil enters the firing tube from such ports 30, it will flow along the walls thereof and will be thoroughly mixed with air flowing axially into the firing tube from the blower 12 and will be burned, partly within the firing tube 10 and in contact with its walls, but largely in a flame discharged from the open end of the firing tube. Such operation will be self-sustaining so long as the oil shut-off valve passes oil.

In such full operation, the supply of air may be so regulated in relation to the setting of the oil metering valve 37, and gasification will be so adequate, that full and proper mixing of air and gas will occur in the firing tube. This not only makes for efficient combustion, but permits the use of a minimum amount of air and hence contributes to efficient operation of the furnace.

The ports 30 and the manifold 27 desirably impose little if any back pressure upon the gas

flowing through them from the gasifying chamber under normal conditions, which prevents any pressure in that chamber from blowing back through the oil line 31. Moreover, the arrangement is self regulating, for if gasification should proceed at too high a rate and cause a rise of pressure in the gasifying chamber, any such pressure would be backed up only by the low head—ordinarily not more than about an inch—of oil in the line from the constant level control, so that such back pressure would diminish the flow of oil, and hence reduce the rate of gas generation, which would promptly reduce the excess pressure.

When the call for heat is satisfied, the oil shut-off valve 36 will be closed, and the supply of oil to the gasifying chamber 21 will be cut off. But gasification of any oil in the gasifying chamber will continue, and its combustion will continue, and the blower will continue to operate, until the residual supply of fuel is exhausted. When this occurs, and the firing tube assembly cools to a sufficient point, the thermostatic element 50 will operate the relay 51 to stop the motor 13 of the blower.

Regulation of the oil burner to meet the differing heat requirements of a considerable range of different installations is readily accomplished by regulation of the metering valve 37 in the oil supply line and by regulation of the vanes 15 at the entrance to the blower. Such regulation is facilitated by the fact that the oil is fed by gravity, under a low pressure head and under a constant level of control close to the bottom of the gasifying chamber 21.

The method of operation and of control in my oil burner provides reliable operation, and the parts are so related as to insure safety. If for any reason the electric power should fail, during full operation the shut-off valve 36 would simply close and combustion would soon terminate for lack of oil supply, while during stand-by operation the valve 36 would simply remain closed regardless of any call for heat. If the independent source of heat for the gasifying chamber 21 should fail, and the oil shut-off valve 36 should open in response to a call for heat, oil would flow into the bottom of the gasifying chamber 21 to the constant level 35. Nothing further would happen. Lacking the independent source of heat, no gasification would occur and the oil would remain liquid and confined in the gasifying chamber below the constant level of control. If, after initial combustion had been established in the firing tube 10, the thermostat 50 or the relay 51 should fail to start the blower motor 13, combustion would nevertheless proceed with air under natural draft, and although in such case combustion would be inefficient, it would be fully self sustaining. If the oil supply should fail, the unit would simply remain, or return to, stand-by operation; while if the oil shut-off valve should fail to be closed fully, or to open fully, the unit would merely continue under or to sustained operation at a reduced rate of consumption, with or without forced draft depending upon whether the temperature of operation was sufficient to cause the thermostat 50 to effect operation of the blower.

In the modification shown in Fig. 6, the gasifying chamber construction is the same as that shown in Figs. 1 to 4, but the firing tube is provided with an upturned elbow 70 so that its flame discharge end 71 is directed vertically upward. In such case, a flame deflector 72 is supported co-axially above the flame discharge end 71 of

the firing tube, conveniently by a post 73 supported in a holder in the elbow 70 and by spider arms 74 at the upper end 71 of the elbow 70. In this modification, the lower part of the gasifying chamber 21 is heated by gas emerging from burner ports 40', and the burner pipe is continued forward and upward to provide a pilot burner 41' just above the flame discharge end 71 of the firing tube.

This modified assembly of Fig. 6 may be carried by a mounting plate identical with the mounting plate 46 shown in Fig. 2, so that it will be interchangeable with the firing tube assembly of Fig. 2 in combination with the operating assembly carried by the base B.

The firing tube assembly shown in Figs. 7 and 8 also discharges vertically. It comprises a firing tube having a horizontal duct 80, an upturned elbow 81 and a vertical tubular portion 82. The outer wall of the vertical portion 82 forms the inner wall of a gasifying chamber 83 formed between such wall and an outer wall 84, and closed at the bottom and top by rings 85 and 86.

An oil inlet pipe 88 is connected to the gasifying chamber 83 through its outer wall 84 and near the bottom of the chamber. The gas outlet from the chamber 83 is into the upper end 89 of a channel 90 running downward along, and welded to, the wall 82 of the firing chamber. Such channel forms a passage leading from the upper part of the gasifying chamber 83 downward and around the elbow 81 to a manifold 91 encircling the firing tube at the lower end of the elbow 81. From the manifold 91, gasified fuel is discharged in the firing tube through ports 92.

To maintain the assembly in stand-by condition ready for automatic starting, the lower end of the gasifying chamber 83 is heated. For this purpose, a gas line 95 runs along below the horizontal section 80 of the firing tube and upwardly to a burner ring 96 encircling the upper end of the elbow 81 just below the bottom ring 85 of the gasifying chamber. A continuation 97 of this gas line extends from the burner ring 96 upward to a point above the top of the firing tube 82 to provide a pilot burner 98.

As in the modification of Fig. 6, this vertical-flame burner is provided with a flame deflector 72, supported on a post 73 coaxial with the vertical portion 82 of the firing tube. Such post may be supported at the bottom by a socket 100 mounted on the inner wall of the elbow 81, and by spider arms 101 engaging the sides of the vertical portion 82.

This modified firing tube assembly may be carried by a mounting plate identical with the mounting plate 46 shown in Fig. 2. It is shown, however, as mounted in a modified form of housing, consisting of a lower casing 110 having an end wall 111 and an intermediate wall 112 respectively at the ends of the horizontal duct 80, and in which the whole assembly is supported, as by welding. The housing 110 supports a vertical casing 114, conveniently of cylindrical form, surrounding the upright portion 82 of the firing tube.

The housing 114 desirably is provided with an opening 115 for lighting the burner ring 96 and to provide, with openings in the walls 111 and 112, the secondary air for the flame from that burner ring 96.

The housing 110—114 desirably supports the firing tube duct 80, the oil line 88, and the gas line 95 in the same relative positions as the firing tube assembly of Fig. 2, so that this assembly can be connected to the same operating unit.

The housing 110—114 provides a duct for the controlled supply of air to the gas burner 96 and to the pilot burner 98, to avoid passage of any excess amount of air through the furnace. In addition, it protects the gas flame, and serves to retain heat in the gasifying chamber 83, for effective operation both under stand-by and full operation conditions.

The operation of the firing tube assembly shown in Figs. 7 and 8 is fundamentally the same as that in Figs. 1 to 4. During stand-by operation, to maintain the lower portion of the gasifying chamber 83 at initial gasified temperature, the gas burner 96 burns continuously, and the pilot burner 98 provides a continuous pilot flame. The oil supply is under constant level control at a level near the bottom of the gasifying chamber 83, at about the level of the section line 8—8, and is under the control of a shut-off valve and a metering valve as in the case of the unit of Figs. 1 to 4. As the oil shut-off valve is opened, oil flows slowly into the gasifying chamber 83, comes into contact with the heated bottom surfaces thereof, and is immediately gasified. The gas so produced flows into and through the channel 99 to the manifold 94, and hence through the ports 92 into the firing tube. The gas is there mixed with air under natural draft to form a combustible mixture which is ignited by the pilot burner 98. The starting cycle of combustion occurs in the same progressive way as in the firing tube of Fig. 2, and when such combustion is well established, the blower is turned on in response to the temperature within the firing tube, by operation of the thermostatic device 50'.

I claim as my invention:

1. An oil-burner, comprising a generally cylindrical firing tube, means forming an annular gasification chamber about the forward flame-discharge end of said cylindrical firing tube and contiguous therewith, the lower portion of said chamber being of oil-retaining form, means forming an annular manifold about the cylindrical firing tube immediately behind the annular gasification chamber and communicating therewith at the top thereof, said manifold being defined in part by the wall of said firing tube, said manifold having a circumferential series of gas-emission ports through the firing-tube wall thereof, said ports being directed at an angle of not to exceed 90° to the cylindrical wall extending forwardly therefrom and being spaced about the periphery of said firing tube and said manifold being otherwise closed, and an oil inlet adjacent the bottom of said gasification chamber, means to admit air at the rear end of said firing tube, whereby oil fed to said firing tube will be gasified adjacent said inlet and the resulting gasified oil will be heated by traverse of the firing-tube wall and will be discharged immediately at high temperature into said cylindrical firing tube in a plurality of circumferentially spaced streams directed into confluence with air flow therethrough toward its flame-discharge end, and the entrance of air to said manifold and gasification chamber will be prevented.

2. An oil burner, comprising a generally cylindrical firing tube disposed generally horizontal and having a forward flame discharge end, means forming an oil gasification chamber surrounding the flame-discharge end of the firing tube contiguous with the outer surface of its wall, the lower portion of said chamber being of oil-retaining form, an oil inlet to said lower portion of said gasification chamber, means forming a manifold

around the firing tube immediately behind the gasification chamber and communicating therewith through a gas outlet port at the top thereof, said manifold being defined in part by the cylindrical wall of the firing tube, the firing-tube wall of the manifold having a series of gas-emission ports therethrough spaced around the periphery of said firing tube, said ports being directed at an angle of not to exceed 90° to the wall extending forwardly therefrom, means to admit oil through said oil-inlet at a metered rate, and means to force air through said firing tube past said gas-emission openings toward the flame discharge end, whereby oil admitted to said gasification chamber is gasified adjacent the bottom thereof and traverses a large area of firing-tube wall to be highly heated before entering said manifold, and admixture of air therewith is avoided prior to its emission into said firing tube.

20. 3. An oil burner as defined in claim 2, in which said oil admitting means comprises an oil-supply line to said oil-inlet, a metering restriction in said line, and a constant level device in said oil-supply line from which oil flows by gravity through said restriction to said oil-inlet and which limits the oil-head in said line to the gravity head from an oil level in said device below the outlet port from the gasification chamber, thereby providing a metered impositive low-pressure oil supply to said oil inlet adapted to be regulated by abnormally high gas pressures in said gasification chamber.

4. An oil burner as defined in claim 2, in combination with ignition means for said firing tube, an oil-supply line to said oil inlet, a constant level device in said oil-supply line from which oil flows by gravity to said oil inlet and which limits the oil-head in said line to a gravity head from an oil level in said device below the outlet port from the gasification chamber, a metering restriction and a shut-off valve in said oil line downstream from said constant level device, and stand-by heating means to heat to initial gasifying temperature prior to oil admission, a bottom wall portion of the gasifying chamber which receives oil initially supplied through said oil line upon the opening of said shut-off valve.

5. An oil burner, comprising a firing tube having a forward flame-discharge end, means forming a gasification chamber about the flame discharge end of the firing tube and contiguous with the outer surface of its wall, means forming a manifold adjacent the rear end of the gasification chamber and communicating therewith through a gas outlet port at the top thereof, a series of gas emission ports from the manifold to the firing tube spaced around the periphery of the firing tube and opening thereto at an angle to avoid entrance thereto of forwardly flowing air in the firing tube, said gasification chamber being adapted to retain oil below said top gas outlet port, an oil inlet adjacent the bottom of the gasification chamber, means to force air through said firing tube forwardly past said gas emission ports, an oil-supply line to said oil inlet, and a constant level device in said oil-supply line from which oil flows by gravity to said oil inlet and which limits the oil head in said line to a gravity head from an oil level in said device below the outlet port from the gasification chamber, thereby providing an impositive low-pressure oil supply to said oil inlet.

6. An oil burner as defined in claim 5 in combination with a metering restriction in the oil-supply line between said constant level device and said bottom inlet to the gasification chamber.

11

7. An oil burner, comprising a firing tube having a forward flame-discharge end, means to pass air forwardly through said firing tube, means forming a gasification chamber about the flame discharge end of the firing tube and contiguous with the outer surface of its wall, means forming a manifold adjacent the rear end of the gasification chamber and communicating therewith through a gas outlet port at the top thereof, a series of gas emission ports from the manifold to the firing tube spaced around the periphery of the firing tube and opening thereto at an angle to avoid entrance thereto of forwardly flowing air in the firing tube, an oil inlet adjacent the bottom of the gasification chamber, ignition means for said firing tube, an oil supply line to said oil inlet and containing a metering restriction and a shut-off valve, stand-by heating means to heat to initial gasifying temperature prior to oil admission a bottom wall portion of the gasifying chamber which receives oil initially supplied through said oil line upon the opening of said shut-off valve, the heat stored in said bottom wall portion by said stand-by heating means being thereby utilized to vaporize the initial metered supply of oil for initial combustion of oil vapor in said firing tube.

8. An oil burner as defined in claim 6, in combination with means to force combustion-supporting air through said firing tube.

9. An oil burner as defined in claim 7 in combi-

12

nation with control means operable subsequent to the opening of said shut-off valve to activate said forced-air means.

10. An oil-burner as defined in claim 7 in combination with control means operable subsequent to the closing of said shut-off valve to inactivate said forced-air means.

GEORGE M. BURGESS.

Certificate of Correction

Patent No. 2,561,264

July 17, 1951

GEORGE M. BURGESS

It is hereby certified that error appears in the printed specification of the above numbered patent requiring correction as follows:

Column 1, line 39, for "part of" read *part in*; line 42, for "to gasifying" read *to a gasifying*;

and that the said Letters Patent should be read as corrected above, so that the same may conform to the record of the case in the Patent Office.

Signed and sealed this 25th day of September, A. D. 1951.

[SEAL]

THOMAS F. MURPHY,
Assistant Commissioner of Patents.
